UNITED STATES PATENT OFFICE.

ARTHUR L. HALLIDAY, OF YONKERS, NEW YORK, ASSIGNOR TO THE BIGELOW CARPET COMPANY, OF CLINTON, MASSACHUSETTS.

DESIGN FOR A CARPET.

SPECIFICATION forming part of Design No. 14,294, dated September 18, 1883.

Application filed August 3, 1883. Term of patent 3½ years.

To all whom it may concern:

Be it known that I, ARTHUR L. HALLIDAY, of Yonkers, in the county of Westchester and State of New York, have invented and produced a new and original Design for a Carpet, of which the following is a full description, in connection with the accompanying photograph, which represents a face view of my new design for a carpet.

10 This invention relates to the new ornamentation of a carpet or analogous fabric. In the accompanying photograph, the letter A represents a central group of flowers, above and below which are groups B B of flowers 15 and leaves. Below the group A is a square figure, a, which is surrounded on two sides by dots and on the other two sides by a castellated border, and which contains a rosette-

like figure in its center. There is also below group A a figure, b, composed of a series of 20 squares that partly overlap one another, and that are in turn overlapped in part by a spray that projects from a floral group, C. In line with the group C of flowers is another group, D, as shown. Near the upper part of the 25 group A is also a figure, d, which is composed of squares.

I claim—

The design for a carpet, the same consisting of the figures A B C D a b d, substantially 30 as shown.

ARTHUR L. HALLIDAY.
